UNITED STATES PATENT OFFICE

KARL PAULI BILLNER, OF NEW YORK, N. Y.

BUILDING CONSTRUCTION AND PROCESS FOR MAKING THE SAME

Application filed August 13, 1927. Serial No. 212,713.

This invention relates to building construction and particularly to composite construction such as may be useful in the construction of floors.

In the present day building industry, one of the greatest demands is for a light material which will have great strength both under shearing stresses and under bending moments. Such constructions not only save material but also reduce the weight to be carried by the foundations of buildings wherein these constructions are installed. This latter result permits of higher buildings with the same foundations and by the saving in material, permits of an increase in the capacity of the building for the same amount of material.

In the blast furnace industry for many years, one of the problems has been to get rid of the slag as a profitable by-product.

The primary object of this invention is the provision of a building construction which will permit of a light construction having great shearing strength, great strength in resisting bending moments as well as great compression strength and at the same time will utilize the slag from blast furnaces, thus giving a large and new outlet for this material as a by-product of the blast furnaces.

Another object of this invention is the provision of a building structure wherein beams or slabs of blast furnace slag forms a light strong body portion which is reinforced by steel.

Another and still further object of this invention is the provision of a blast furnace slag beam or slab having reinforcements in its body to provide additional strength with and a closer union between the body portion and the reinforcement than is possible with the usual concrete structures.

In the illustrated embodiment of my invention I have shown how the same can be applied to a floor construction. I have illustrated how the beams or the plates can be laid on the usual joists.

While the reinforcing means which I may put in the body of the element which I use to make up the body of the structure such as a floor, may have a corresponding position to

a similar reinforcement in an ordinary concrete structure, it is believed that I obtain a very much stiffer and stronger structure due to the similarity in the molecular make-up of the slag and for example, steel reinforcement which I may use. It is well known that there is greater cohesion between similar compositions than between dissimilar compositions. For this reason I obtain a stronger union between the slag and the metallic reinforcement than could ever be possible with a combination of, for example, steel and Portland cement. A further object of my invention is, therefore, to provide an improved reinforced element for use in building construction wherein the reinforcement will be closely connected to the body of the element.

A still further object is to provide a process for the production of such an element.

Fig. 1 is a perspective view illustrating my invention as applied to a floor construction, portions being broken away.

Fig. 2 is a perspective view of one of the elements.

Fig. 3 is a view similar to Fig. 2 but showing a different construction for the side wall slots.

Fig. 4 is a cross section on the line 4—4 of Fig. 2.

Fig. 5 is a cross section on the line 5—5 of Fig. 3.

Fig. 6 illustrates a modified form in cross section.

Fig. 7 illustrates a cross section of my invention on a plane passing through the reinforcing bars.

10 designates I-beams which may form the main support of a floor, 11 being concrete supporting members which may be of concrete poured around the lower portion of the I-beam.

The elements which form my invention I have designated by the numerals 12, 12^a, 12^b. These elements are composed of slag, preferably of the porous variety and are cast around the reinforcements 13, and 13^b respectively. The moulds in which these elements are cast may be provided with plates at the sides provided with ribs which will form recesses 14, 14^a and 14^b respectively.

In pouring these elements, any suitable method for causing the slag to be porous may be utilized. For example, steam may be blown into the slag or the plates which form the sides of the moulds may be wet or both methods or any other suitable method may be used.

In assembling the elements into the floor structure, reinforcing rods such as 15, 15^a and 16 15^b may be utilized by placing them in the recesses 14, 14^a and 14^b and by a suitable cement or other plastic material which will harden the reinforcing means may be held rigid with relation to the elements 12, 12^a and 12^b which in the present illustrating embodiment are shown as beams. This cement or other plastic material also acts as a binder and reinforcing medium to prevent movement between the elements or beams and to transmit the strains 20 placed upon one to the adjacent ones.

The type of reinforcing means 15^a in the form shown in Fig. 3 would naturally assume the shape of the recess 14^a, the particular type of recess being dependent upon the type of 25 duty to be performed by the building construction. In Fig. 1, I have shown a concrete grout 16 filling the spaces between the elements 12, and a portion of a floor fill 17 broken away at the upper edge of the figure. In Fig. 30 7, I have illustrated one form of reinforcement, the rods being placed so that near the middle of the span of the element the reinforcing means will be adjacent the bottom and at the outer ends will extend up and over the 35 position to be occupied by the I-beams of the floor structure when the assembly is complete. The reinforcing means shown at 13 of Fig. 2 may be omitted from the element as shown in 12^a if this is found to be desirable. In the 40 structure shown in Fig. 3, the reinforcing means 15^a and the cement or other plastic material which binds the reinforcing means in place, will act as the reinforcing agent for the element 12^a.

45 It is believed that by the use of slag as herein set forth, such as blast furnace slag that a very advantageous and useful building element may be had which attains the objects of the invention as above set forth, which will 50 be cheap of manufacture and will assist the blast furnace manufacturers in disposing of their slag at considerable profit.

It is to be understood that the particular embodiment described in detail and illustrated 55 in the drawing is not to be construed as limiting the application of the invention and that modifications and changes may be made without departing from the spirit of the invention and within the scope of the appended 60 claims.

Having described my invention, what I claim and desire to secure by Letters Patent of the United States is:—

65 1. A building structure comprising relatively long pieces of blast furnace slag cast

molten in complementary shapes and means for reinforcing the slag pieces the body of the slag being porous to reduce its weight.

2. A building structure comprising pre-constructed strips of porous molten-cast blast 70 furnace slag, said strips being placed side by side and means between the strips for locking them together.

3. A building structure comprising pre-constructed beams of porous molten-cast blast 75 furnace slag, said beams being side by side, a beam having a recess in a side adjacent to an adjacent beam, a reinforcing means having a portion within the recess.

4. A building structure comprising pre-constructed beams of porous molten-cast blast furnace slag, said beams being side by side, reinforcing means within the bodies of the beams, the beams having recesses in their sides, reinforcing means in the recesses and 80 means for filling the spaces in the recesses around the reinforcing means.

5. A building element comprising a relatively long piece of porous molten cast blast furnace slag.

6. A building element comprising a relatively long piece of porous molten cast blast furnace slag having a recess on one side.

7. A building element comprising a relatively long piece of porous molten cast blast 95 furnace slag having a reinforcement within its body portion.

8. A building element comprising a relatively long piece of porous molten cast blast furnace slag having steel reinforcing means 100 extending substantially throughout its length, and having a recess on one of its long sides.

9. The process of preparing a building element which comprises the placing of metallic reinforcing means in a mould, treating blast 105 furnace slag so that it will be porous and pouring the slag into the moulds while the slag is in a hot liquid state.

10. The process of preparing a building element which comprises the preparation of a 110 mould, the placing of damp plates therein at the sides thereof, the placing of metallic reinforcing means in the mould and pouring hot liquid slag into the mould.

11. The process of preparing a building element which comprises the preparation of a mould, the placing of damp plates therein at the sides thereof, the placing of metallic reinforcing means in the mould, treating slag so 115 that it will be porous and pouring the slag into the moulds while the slag is in a hot liquid state.

In testimony whereof I hereunto affix my signature.

KARL PAULI BILLNER. 125
